UNITED STATES PATENT OFFICE.

WILLIAM JOSEPH HICKEY, OF WESTWOOD, CALIFORNIA, ASSIGNOR TO JOHN E. SPIRES,
OF LOS ANGELES, CALIFORNIA.

CLAMP FOR CONCRETE-CURBING FORMS.

Application filed August 5, 1926. Serial No. 127,321.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as herein-after claimed; and objects and advantages, 10 other than those specifically mentioned, are included within its scope.

My invention relates to means for supporting concrete form lumber and its principal object is to provide an improved clamp 15 for this purpose that can be conveniently applied and removed, and that is especially adapted for making straight and curved concrete curbing. Another object is to furnish ready means for adjustment whereby 20 walls or curbing of different thickness can be constructed with either straight or sloping faces.

My objects are attained in the manner illustrated in the accompanying drawing 25 which is a perspective view of the complete invention.

My improved clamp comprises a pair of opposed upright stanchions 5 of T section, with their flanges 6 inside and their stems 30 extending outwardly. These stanchions are pivotally connected to a cross bar 7 at the top by means of bolts 8 and clamp nuts 9. For adjusting the spacing of stanchions at the top, the cross bar is provided with a plurality of round bolt holes as at 10, or with 35 slotted bolt holes as at 11.

The cross bar overhangs the stanchions at each end and its extremities are connected to intermediate portions of the respective stanchions by means of longitudinally extensible 40 diagonal braces 12. These braces are pivotally connected to the cross bar and stanchions by means of rivets 13, and their length is adjusted by means of bolts 14 and clamp nuts 15. Each of the brace bars is provided with guide lugs 16 at its extremity for engaging the edges of its cooperating bar, and the two bars of each brace are mutually guided in this manner to provide 45 extensibility. Bolts 14 pass through a hole in one of the brace bars and a slot 17 in the 50 other.

The lower ends of the stanchions are slotted 18 and are provided with vertically

slidable drive pins 19 having rivets 20 passing through the slots. The drive pins are guided by the rivets and the flanges 6 against which they abut. The upper ends of the drive pins are folded over as at 21 to form 55 heads for hammer driving.

Each of the stanchions is provided with a 60 slidable C clamp 22 engaging the edges of its flanges. These clamps have inwardly extending integral stems 23 which are slotted vertically at their ends. Jaw bars 24 engage 65 these slots and are pivoted therein at 25. The upper ends of the jaw bars are tapped and provided with crank bolts 26 adapted to engage the stanchions. In this manner 70 the form lumber indicated by dotted lines 27 can be clamped between the jaw bars and the stanchions by tightening up the crank bolts 26.

It will be apparent from the foregoing 75 description that to make use of my invention for curbing construction the lower ends of the stanchions are first placed upon the ground at the bottom of the excavated trench. The drive pins 19 are then driven down and serve to hold the stanchions in 80 place. The form lumber is then placed and held in position by means of jaw bars 24 and crank bolts 26.

I particularly desire to emphasize that the 85 several adjustments provided in my device enable it to be used for curbing or walls of different thickness, and with either one or both faces of the wall sloping at any desired angle.

Having thus fully described my invention, 90 I claim—

1. A device of the character described comprising; a pair of upright stanchions; drive pins at the lower ends of the stanchions longitudinally slidable thereon and adapted 95 for extending therebelow; a cross bar engaging the upper ends of the stanchions adapted for variably spacing them; and releasable means for holding form material against the inner faces of the stanchions.

2. A device of the character described comprising; a pair of upright stanchions; drive pins at the lower ends of the stanchions longitudinally slidable thereon and adapted for extending therebelow; a cross 105 bar engaging the upper ends of the stanchions adapted for variably spacing them and having overhanging extremities; and

diagonal braces of variable length pivotally connecting said extremities to intermediate portions of the adjacent stanchions.

3. The construction set forth in claim 2 in combination with longitudinally slideable clamps on the stanchions adapted for holding form material against the inner faces of the stanchions.

4. The construction set forth in claim 2 in combination with longitudinally slideable clamps on the stanchions adapted for holding form material against the inner faces of the stanchions; the engagement between the upper ends of the stanchions and cross bar being pivotal.

WILLIAM JOSEPH HICKEY.
